CONCEALED HINGE

Joseph Soss, Roselle, N. J.

Application December 7, 1935, Serial No. 53,354

16 Claims. (Cl. 16—164)

This invention relates to concealed hinges; and the object of the invention is to provide a hinge of the class described consisting of two butt parts, with links for movably coupling said butt parts and wherein one butt part is in the form of a hook-shaped arm having a housing portion concealing the links of the hinge; a further object being to provide a hinge of the class described, the hook-shaped butt part of which is provided with an attaching plate portion so constructed as to facilitate quick attachment and detachment thereof with respect to a support or a supplemental butt part secured to or forming part of said support; a further object being to provide a hinge of the class described which, in addition to being strong and durable in construction, will also present a neat and finished appearance when the butt parts are in open position; and with these and other objects in view, the invention consists in a hinge of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

30 Fig. 1 is a horizontal sectional view through two supports showing one of my improved hinges mounted in connection therewith, the section being on the line 1—1 of Fig. 3.

Fig. 2 is a view similar to Fig. 1 but showing 35 both butts of the hinge in section and with the swinging member in open position.

Fig. 3 is a section on the line 3—3 of Fig. 1.

Fig. 4 is a view similar to Fig. 1 showing a modified form of hinge and showing part of the 40 construction in full lines.

Fig. 5 is a sectional view through both butts of the hinge shown in Fig. 4 of the drawing, with the swinging member in open position.

Fig. 6 is a partial section on the line 6—6 of Fig. 4; and

Fig. 7 is a view similar to Fig. 1 showing another modification.

In the accompanying drawing, I have indicated at 10 a part of the body of a motor vehicle; and at 11, a door mounted in connection with the body 10 by one of my improved hinges 12 shown in Figs. 1, 2 and 3 of the drawing and with a modified form of hinge 12a shown in Figs. 4, 5 and 6. The door 11 is provided with a projecting flange 13 at the hinged side thereof to close the

space formed between adjacent walls 14 and 15 of the door and body of the vehicle respectively.

The hinge shown in Figs. 1 to 3 inclusive consists of a housing butt part 16 and a hook-shaped arm 17 which is movably coupled with the housing 16 by links 18 and 19 arranged on fixed pivot pins 20 and 21 respectively in the housing 16 or the top and bottom walls 22 and 23 thereof, whereas the free ends of said links are pivotally supported in connection with pins 24 and 25 mounted in connection with the hook-shaped butt part 17, the pin 24 projecting beyond the upper and lower surfaces of the link 18 and butt part 17 and adapted to be slidably mounted in arc-shaped or semi-circular channels 26 formed on 15 the inner adjacent surfaces of the top and bottom walls 22 and 23 of the butt housing 16.

The top and bottom walls of the butt housing 16 are joined at one side by a vertical wall 27 which forms a substantially U-shaped body of 20 said housing. The forward edges of said top and bottom walls have laterally extending flanges 28 to provide for the attachment or mounting of 25 said butt 16 in connection with the body 10 of the vehicle by welding, riveting or by screws or bolts in customary ways. The grooves 26 open outwardly through one side of the top and bottom walls 22 and 23 as indicated at 29, Fig. 2 of the drawing, to facilitate the mounting of the pin 24 therein.

In Fig. 3 of the drawing, the top and bottom walls 22 and 23 are drawn inwardly to form bushings 30 around the pins 20, 21 so as to provide longer bearings for the pins in said plates, and at the same time, to provide additional bearings 35 for the links 18 and 19 in the butt 16.

The butt 17 in the construction shown in Figs. 1 to 3 inclusive is fashioned from two primary sheet metal parts which may be welded or otherwise secured together, namely, an outer relatively thin hood part 31 and an inner heavier elongated strip or sheet 32 fashioned to form the desired curvature of the hook-shaped part 17. The outer side wall 33 of the part 31 is of a similar curvature so that the part 32 will fit or seat 40 snugly upon the wall 33 as clearly seen in Fig. 2 of the drawing.

One end of the inner part 32 is reduced in width and curled to form a cylindrical pintle bearing 34 which fits within a recess 35 formed 50 at the corresponding end portion of the link 18 in the manner clearly illustrated in Fig. 3 of the drawing. The central portion of the part 32 is cut and curled to form another cylindrical pintle bearing 36 arranged in the same 55

horizontal alignment with the bearing 34 and which is adapted to fit and operate in a recess 37 formed in the link 19 as indicated in Fig. 2. The upper and lower edges of the part 32 and 5 upper and lower surfaces of the links 18 and 19 fit snugly within the upper and lower walls 38 and 39 of the hood part 31 of the butt 17. These walls are of the contour clearly indicated in Fig. 1 of the drawing and form a chamber 10 or recess inwardly of the part 32 and between the walls 38 and 39 in which the links 18 and 19 are concealed. From the point 40 at the free end of the butt part 17 to the point 41, the outer wall 33 of the part 31 covers and 15 conceals the hinge parts at the outer exposed surface thereof, so as to render the links 18 and 19 substantially invisible from the door opening when the door is in open position.

The other end of the part 32 is provided with 20 an angularly arranged attaching plate portion 42 having upper and lower projecting flanges 43 over which the top and bottom plates 38 and 39 are adapted to pass, and pins 44 are adapted to be passed through the plates 38, 39, flanges 25 43, and through a mounting plate 45 for detachably coupling the butt 17 with the door 11. The plate 45 is welded, rivets or otherwise secured to the wall 14 of the door to constitute a 30 more or less permanent part thereof and provides means including the pins 44 for detachably mounting the butt 17.

By reason of the construction employed, the butt 17 may be produced at a very nominal cost, 35 especially in employing the thin shell or hood part 31 which may be readily shaped into the U-shaped cross sectional contour employed throughout the length of the hook-shaped arm portion of said butt, whereas the heavier part 40 32 is simply in the form of a strip which is curled to form the pintle bearings 34 and 36 and fashioned to form the attaching flanges. Where direct connection of the part 17 with the support is desired, the flanges 43 and plate 45 is eliminated. However, in some forms of 45 construction, it may be desirable to construct the hook-shaped butt part from a single body, in which event, the same may be formed from a heavy sheet of metal by die forming or coining or by a forging operation, or in some cases, 50 the same may constitute a cast or molded body.

In Figs. 4, 5 and 6 of the drawing, I have shown at 46 a butt member substantially similar in general contour to the member 17 shown in 55 Figs. 1 to 3 inclusive, but which consists in a unitary body having a continuous outer side wall 47 having top and bottom walls 48 to which the links 18a, 19a are pivoted on pins 24a, 25a. The ends of the links 18a, 19a arranged on said pivot 60 pins are solid and not cut away as with the links 18 and 19. The pins 24a and 25a are supported in the top and bottom walls 48 of the butt 46.

The butt 46 is detachably coupled with a coupling or mounting plate 45a substantially similar to the plate 45, by pins 44a which pass 65 downwardly through the walls 48 or upper and lower extensions 48a thereof which form mounting flanges similar to the flanges 43 of the butt part 32.

With the hinge shown in Figs. 4, 5 and 6, a 70 butt member or housing 16a substantially similar to the housing 16 is employed, the only difference being that the bushings or bearings 38a are drawn slightly longer to compensate for the 75 difference in thickness of the metal at the top

and bottom of the butt member 46. In said figures, I have indicated at 20a and 21a the pins in connection with which the links 18a and 19a are pivotally mounted in the butt housing 16a.

In Fig. 7 of the drawing, I have shown another modification of the hinge shown in Figs. 1 to 3 inclusive, wherein a butt member 49 is substituted for the butt member 16 and a butt member 50 is substituted for the member 17. 10 With this construction, the butt member 50 consists of an outer hook-shaped shell portion 51 composed of relatively thin metal and an inner thicker butt part 52 in the form of a strip of metal curled at one end to form a pintle bearing 15 53 similar to the bearing 34. The other end portion of said strip is extended angularly to form an attaching plate portion 54 which may be screwed, bolted or otherwise secured to a suitable supporting frame. Substituted for the cylindrical pintle bearing 36 shown in Figs. 1 to 3 inclusive, I employ a cylindrical pintle bearing 55 formed on a separate strip or plate 56 which is fashioned to fit within the strip 52 including the attaching plate portion 54 thereof and 20 may be welded or riveted thereto. The outer shell or housing portion 51 of the butt 50 will have top and bottom walls, the same as provided on the part 31 shown in Figs. 1 to 3 inclusive and the bottom wall as indicated at 25 51a in Fig. 7. These walls extend over and cover the upper and lower edges of the butt part 52 including the bearing portions 53 and 55, the latter constituting part of the strip 56.

With the structure shown in Fig. 7, I also 30 substitute for the links 18 and 19 shown in Figs. 1 to 3 inclusive sheet metal links 57 and 58, the link 57 having cylindrical bearings at its ends, one of which operates upon a pin 59 passed through the bearing 53 and also through 35 the top and bottom walls of the shell part 51. The other cylindrical bearing of the link 57 operates on a pin 60 mounted in the butt member 49 as indicated in Fig. 7. The link 58 is 40 offset centrally thereof as indicated at 61 and is provided with cylindrical pintle bearings at its ends, one mounted upon a pin 62 which also passes through the bearing 55 in the top and bottom walls of the butt part 51. The cylindrical bearing at the other end of the link 58 is mounted upon a pin 63 supported in the 45 butt member 49 as indicated.

With the construction shown in Fig. 7, I have 50 omitted the extension of the pintle pins 59 and 55 have also omitted the grooves upon adjacent and spaced walls of the butt member 49, in other words, similar to the grooves 26 shown in Figs. 1 to 3 inclusive. The use of these 55 grooves is not absolutely necessary in any of the forms of construction employed.

Links of the general construction of the links 57 may be substituted for the links 18, 19, 18a, 19a shown in Figs. 1 to 6 inclusive, especially in the construction of a more economical type of hinge.

With all forms of hinges shown, I provide hook-shaped butt parts having hollow or recessed side surfaces closed by an outer hood wall and top and bottom walls which conceal the links of the hinge from view at the door opening when the door is in open position, thus producing a neat and finished appearance and maintaining the paint, lacquer or other finish coating which may be applied to said hook-shaped arm as well as other parts of the hinge, in proper condition at 70 75

all times. A hook-shaped hinge butt of the cross-sectional contour employed will be strong and durable in use, and by reason of the manner of constructing the same, may be sold at a low price, making it possible to utilize concealed hinges in the mounting of doors or swinging members in connection with their supports, which would otherwise be impossible by virtue of the cost of production of hinges of the concealed type 10 under the methods heretofore known.

In addition to the strength, economy and appearance of a hinge made according to my invention, I also provide a hinge which is protected, to a major degree, from the collection of dust 15 and dirt and which will present a neat and finished appearance at all times. My invention is not limited to the particular cross sectional contour of the hook-shaped butt member herein disclosed, nor to the specific form and arrangement 20 of the links and the butt housing employed, as these parts will be modified to suit the particular type of installation employed and the swing or throw of the hinge desired.

Having fully described my invention, what I 25 claim as new and desire to secure by Letters Patent, is:

1. A concealed hinge comprising two butts, one of said butts comprising a housing portion and the other butt being in the form of a hook-shaped 30 arm having top and bottom walls forming a hollow chamber on one surface of the arm and links pivotally supported in the housing butt part and partially arranged within the hollow chamber of said arm and pivotally coupled with the 35 top and bottom walls of said arm for coupling said butts together.

2. A concealed hinge comprising two butts, one of said butts comprising a housing portion and the other butt being in the form of a hook-shaped 40 arm having top and bottom walls forming a hollow chamber on one surface of the arm and links pivotally supported in the housing butt part and partially arranged within the hollow chamber 45 of said arm and pivotally coupled with the top and bottom walls of said arm for coupling said butts together, and means on opposed walls of the housing butt for guiding the pivot between one of the links and said hook-shaped butt part in its movement relatively to the housing butt 50 part.

3. A concealed hinge comprising two butts, one of said butts comprising a housing portion and the other butt being in the form of a hook-shaped arm having top and bottom walls forming a hollow 55 chamber on one surface of the arm and links pivotally supported in the housing butt part and partially arranged within the hollow chamber of said arm and pivotally coupled with the top and bottom walls of said arm for coupling said butts 60 together, means on opposed walls of the housing butt for guiding the pivot between one of the links and said hook-shaped butt part in its movement relatively to the housing butt part, and said hook-shaped butt part having an attaching end portion consisting of spaced flanges.

4. In a hinge of the class described, a hinge butt, said butt comprising a curved, hollow body portion consisting of an outer side wall extending continuously throughout substantially the full length of said butt, and top and bottom wall 70 portions continuous with the upper and lower edges of said outer side wall, and said upper and lower wall portions having longitudinally spaced pintle receiving portions arranged in vertical alignment with each other.

5. In a hinge of the class described, a hinge butt, said butt comprising a curved, hollow body portion consisting of an outer side wall extending continuously throughout substantially the full length of said butt and top and bottom wall portions continuous with the upper and lower edges of said outer side wall, said upper and lower wall portions having longitudinally spaced pintle receiving portions arranged in vertical alignment with each other, and means inwardly of the top, bottom and side walls of said butt for forming other spaced pintle engaging portions. 10

6. In a hinge of the class described, a hinge butt, said butt comprising a curved, hollow body portion consisting of an outer side wall extending 15 continuously throughout substantially the full length of said butt and top and bottom wall portions continuous with the upper and lower edges of said outer side wall, said upper and lower wall portions having longitudinally spaced pintle receiving portions arranged in vertical alignment with each other, means inwardly of the top, bottom and side walls of said butt for forming other spaced pintle engaging portions, and said last named means comprising a supplemental sheet 20 metal butt part fitting snugly within and secured to the first named part.

7. In a hinge of the class described, a hinge butt fashioned from sheet metal butt parts, one of said parts comprising an elongated curved 30 wide sheet metal strip curled at one end thereof to form a cylindrical pintle bearing projecting at the concave side of said curved butt part, another cylindrical bearing projecting from the concave side of said strip intermediate the ends thereof, and another butt part comprising a thin sheet metal shell consisting of an outer curved side wall and top and bottom walls continuous with the upper and lower edges of the side wall and projecting over the upper and lower edges 35 of both of said cylindrical bearings.

8. In a hinge of the class described, a hinge butt fashioned from sheet metal butt parts, one of said parts comprising an elongated curved wide sheet metal strip curled at one end thereof to form a cylindrical pintle bearing projecting at the concave side of said curved butt part, another cylindrical bearing projecting from the concave side of said strip intermediate the ends thereof, another butt part comprising a thin 40 sheet metal shell consisting of an outer curved side wall and top and bottom walls continuous with the upper and lower edges of the side wall and projecting over the upper and lower edges 45 of both of said cylindrical bearings, said butt parts being welded together, and one of said butt parts including projecting mounting flanges for securing the hinge butt in connection with a support.

9. In a concealed hinge, a hinge butt, said butt comprising a curved hollow body portion consisting of an outer wall extending throughout the length of said butt and including wide upper and lower angularly extending and longitudinally arranged flanges, and said flanges having longitudinally spaced pintle apertures. 60

10. In a concealed hinge, a hinge butt, said butt comprising a curved hollow body portion consisting of an outer wall extending throughout the length of said butt and including wide upper and lower angularly extending and longitudinally arranged flanges, said flanges having longitudinally spaced pintle apertures, and one end portion of said butt being relatively wide and including coupling flanges. 70

11. In a concealed hinge, a hinge butt, said butt comprising a curved hollow body portion consisting of an outer wall extending throughout the length of said butt and including wide upper and lower angularly extending and longitudinally arranged flanges, said flanges having longitudinally spaced pintle apertures, one end portion of said butt being relatively wide and including coupling flanges, and a coupling plate on the wide end portion of said butt and within said coupling flanges.

12. In a concealed hinge, a hinge butt, said butt comprising a curved hollow body portion consisting of an outer wall extending throughout the length of said butt and including wide upper and lower angularly extending and longitudinally arranged flanges, said flanges having longitudinally spaced pintle apertures, and said butt being composed of independent sheet metal parts arranged one within the other and secured together.

13. In a concealed hinge, a hinge butt, said butt comprising a curved hollow body portion consisting of an outer wall extending throughout the length of said butt and including wide upper and lower angularly extending and longitudinally arranged flanges, said flanges having longitudinally spaced pintle apertures, said butt being composed of independent sheet metal parts arranged one within the other and secured together, and the outer sheet metal part being thinner than the inner part.

14. A hinge of the class described comprising two butt parts, one of said parts being in the form of a U-shaped housing having spaced bearing walls, the other butt part consisting of spaced bearing walls disposed adjacent the inner surfaces of the bearing walls of the first named butt part, a pair of links of a width equal to the distance between adjacent surfaces of the bearing

walls of the second named butt part, means for pivoting the links to the bearing walls of both butt parts and the second named butt part having a curved outer wall continuous with the bearing walls of said part and forming a housing concealing the links of the hinge. 5

15. A hinge of the class described comprising two butt parts, one of said parts being in the form of a U-shaped housing having spaced bearing walls, the other butt part consisting of spaced bearing walls disposed adjacent the inner surfaces of the bearing walls of the first named butt part, a pair of links of a width equal to the distance between adjacent surfaces of the bearing walls of the second named butt part, means for pivoting the links to the bearing walls of both butt parts, the second named butt part having a curved outer wall continuous with the bearing walls of said part and forming a housing concealing the links of the hinge, and means for detachably mounting the second named butt in connection with its support. 10 16

16. A hinge of the class described comprising two butt parts, one of said parts being in the form of a U-shaped housing having spaced bearing walls, the other butt part consisting of spaced bearing walls disposed adjacent the inner surfaces of the bearing walls of the first named butt part, a pair of links of a width equal to the distance between adjacent surfaces of the bearing walls of the second named butt part, means for pivoting the links to the bearing walls of both butt parts, the second named butt part having a curved outer wall continuous with the bearing walls of said part and forming a housing concealing the links of the hinge, and the second named butt being formed from two sheet metal parts arranged one upon the other and secured together. 20 25 30 35

JOSEPH SOSS. 40
